UNITED STATES PATENT OFFICE

2,506,679

VIBRATO SYSTEM FOR ELECTRICAL
MUSICAL INSTRUMENTS

James A. Oswald, Chicago, Ill., assignor to Central Commercial Company, Chicago, Ill., a corporation of Illinois

Application February 1, 1947, Serial No. 725,848

5 Claims. (Cl. 84—1.25)

1

This invention relates to the art of electrical musical instruments, and, more particularly, to a novel and improved vibrato system for instruments of the described character.

Conventional electrical musical instruments generally comprise a plurality of oscillation generators of the space discharge tube type of which one is provided for each note of the entire range of the instrument. The most common practice at the present time to obtain good frequency stability is to provide twelve so-called master oscillators which are of high quality and possess excellent frequency stability. Each of these master oscillators is tuned to a different note of a single octave of the equally tempered scale and controls the frequencies of a cascaded set of octavely related slave oscillators. As the frequency relationship of these so-called slave oscillators is determined by that of the respective master oscillators, they may be relatively simple and inexpensive in character whereby substantial savings may be accomplished in the cost of the entire instrument. An electrical musical instrument of this general type is disclosed in the Larsen Patent #2,403,090, wherein each master oscillator stabilizes a set of octavely related slave oscillators of the multi-vibrator type.

As an interesting modification of this principle embodied in most electronic organs mention is made of the use of cascaded aperiodic frequency dividing circuits, such as Eccles-Jordan circuits, a cascaded set of which is coordinated to each master oscillator. While these circuits are incapable of independent oscillation, they are capable of deriving octavely related output signals for any input signal frequency. Electrical musical instruments of this type are disclosed in the copending U. S. patent of Nicholas Langer, No. 2,486,039, dated October 25, 1949 and entitled "Electrical musical instrument."

In all electrical musical instruments, it is desirable to provide for slight frequency modulation of the oscillations produced. This is carried out at a very slow rate in the range of about 6 cycles per second and gives rise to a very attractive musical effect, commonly called vibrato. As in electrical musical instruments of the master-controlled slave oscillator type the frequencies of the slave oscillators directly follow those of the master oscillators a good vibrato effect may be obtained by frequency-modulating the master oscillators. Various difficulties were, however, experienced in carrying this principle into practice. A master oscillator in order to provide its characteristic stabilizing function upon a set of

2

cascaded slave oscillators has to be of extremely high stability. On the other hand, an oscillator which may readily be frequency-modulated is characterised by relatively low frequency stability. Obviously, these two conditions are mutually exclusive. Thus, while frequency modulation of some oscillators may be accomplished by electrode voltage shifts, for example, these circuits are inherently not sufficiently stable to permit their satisfactory use in musical instruments which have to maintain their tuning for long periods of time. That is to say, if a frequency modulation or vibrato effect may be obtained by intentionally varying electrode voltages of the oscillator tube, then any random variation in electrode voltages will likewise produce a shift in frequency. This would necessitate the use of voltage regulated power supply sources and would also mean that any change in tube characteristics would detrimentally influence the tuning of the instrument.

In the Larsen patent referred to in the foregoing, there is disclosed a vibrato system which provides a practical solution of the outstanding problem. In this system, each master oscillator comprises a triple grid super control amplifier tube which is electrically associated with a frequency determining LC or tank circuit to constitute an electron coupled tuned grid oscillator. Frequency modulation of each master oscillator is accomplished by means of an individual triode tube, the plate circuit of which is in series with a capacitor shunted across the tank circuit. A vibrato signal derived from an oscillator of very low frequency, for example 6 cycles per second, is simultaneously impressed upon the grids of all of the said triodes in such a manner that the resulting variations in the plate resistance of the said triodes will produce variations in the capacitive reactance in the tank circuits, which, of course, will cause frequency modulation of all master oscillators at the desired vibrato rate. It will be noted that in this vibrato system the individual triode tubes coordinated to each master oscillator function not only as amplifiers of the vibrato signal but also serve to isolate the master oscillators from the common vibrato oscillator.

While the Larsen vibrato system provides excellent results, it has the disadvantage that it requires a relatively complicated circuit including 12 triode tubes. The necessary addition of such a large number of tubes, with their sockets and circuit elements and power requirements have materially increased the cost of the entire instrument. Although various other suggestions and

proposals were made to solve the outstanding problem, none, as far as I am aware, of these suggestions and proposals have been completely satisfactory and successful when carried out on a practical and commercial scale.

I have discovered that the heretofore mentioned problem may be solved in a remarkably simple manner.

It is an object of the present invention to provide a vibrato system for electrical musical instruments which avoids the difficulties and inconveniences connected with prior vibrato systems.

It is another object of the present invention to provide a vibrato system of novel and improved character which permits the frequency modulation of a set or group of master oscillators by a common vibrato oscillator without resorting to separate and individual isolating and amplifying tubes, while retaining the normal and desirable high frequency stability characteristics of the master oscillators.

It is a further object of the invention to provide a greatly simplified vibrato system for electrical musical instruments in which the vibrato effect is produced by a novel circuit organization of the master oscillator whereby frequency modulation of the oscillator may be accomplished at practically no extra cost and without the addition of any extra tubes or circuit elements.

It is also within the contemplation of the present invention to provide a novel master oscillator for electrical organs comprising a pentode tube employed in such a circuit as to function as two virtual three-element tubes, one of which is utilized as an electron-coupled oscillator of great frequency stability while the other functions as a frequency modulating tube and is instrumental in producing the vibrato effect.

The invention also contemplates a vibrato system for electrical organs of the master-slave oscillator type which is extremely simple in construction, compact in character and which may be incorporated into an organ at practically no extra cost except for that of a vibrato signal generator.

Other and further objects and advantages of the invention will become apparent from the following description, taken in conjunction with the accompanying drawings; in which:

Figure 1 is the circuit of a master oscillator, including means for frequency-modulating the output of the same at vibrato rate, embodying the principles of the present invention;

Figure 2 is a block diagram showing the basic circuit organization of a group of master oscillators, frequency-modulated by a common vibrato signal oscillator, and each associated with a group of slave oscillators; and

Figure 3 is the circuit of a preferred form of vibrato signal generator.

Broadly stated, according to the principles of my invention, I provide a group of twelve master oscillators, each of which comprises a tube of the pentode type electrically associated with a tank circuit to constitute an electron coupled oscillator. The electron coupled oscillator has the advantage that in an oscillator of this type the screen and plate supply voltages can be so arranged that a shift in the primary supply voltage may be compensated in such a way that there will be no resulting shift in operating frequency.

In an electron coupled oscillator, the oscillatory circuit is electrically associated with the first three elements of the tube, namely, the cathode,

control grid and the screen grid, the screen grid performing the function of anode for the triode oscillator thus formed. Most of the electrons of the electron stream emitted by the cathode and moving towards the screen grid of small physical dimensions are going to miss the screen grid, and proceed towards the anode of the tube. This makes the screen grid in effect a virtual cathode for the second triode unit constituted by the screen grid, suppressor grid and plate.

In the normal practice of designing electron coupled oscillators, this second triode unit functions as an amplifier for the oscillations generated in the oscillatory circuit and also serves to isolate the said oscillatory circuit from load variations in the output circuit. In contrast to this, in accordance with the invention, the second triode unit is utilized not only as an amplifier but also as a frequency modulating device acting upon the oscillatory circuit associated with the first triode unit.

In the foregoing, the system formed by the screen grid, suppressor grid, and plate was likened to a triode. It is possible, therefore, to vary the effective plate resistance of this virtual triode by impressing a signal upon its "control" grid, which is the suppressor grid of the pentode. By connecting a capacitor from the hot end of the tank circuit to the plate of the tube, the plate resistance of the said virtual triode and the said capacitor in series therewith will be shunted across the tank circuit. Since the virtual cathode of the system, that is the screen grid, is at ground potential with respect to A. C. signals, by supplying the suppressor grid with a vibrato signal of very low frequency, such as approximately 6 cycles per second, a corresponding frequency shift will be obtained, so that the output signal taken from the plate of the tube will be frequency modulated and also will be amplitude modulated to a slight extent. This frequency modulated signal is fed to a cascaded group of octavely related slave oscillators upon which the amplitude variations present in the output signal will have no effect, so that a pure frequency modulation or vibrato effect will remain.

In order to give those skilled in the art a better understanding of the invention, reference is made to Figure 1 of the drawing which is a preferred form of circuit organization of a frequency modulated master oscillator embodying the principles of the present invention. Reference character V-1 denotes a space discharge tube of the pentode type having a cathode 10, a control grid 11, a screen grid 12, a suppressor grid 13 and an anode or plate 14. For the sake of clarity, illustration of the conventional heater of the cathode has been omitted. Plate voltage of suitable value is applied to plate 14 from a source 15, connected to terminal A, through a dropping resistance R-1, and screen voltage of appropriate value is applied to screen grid 12 from a tap B on a voltage divider resistance R-2 connected between A and the ground. While point B is substantially above ground potential as far as D. C. potential is concerned, it is effectively at ground potential for any A. C. component present due to the connection of a by-pass condenser C-2 between tap B and ground.

A tank circuit comprising inductance L-1 and capacitor C-1 has one of its terminals 16 connected to control grid 11 of tube V-1 through a small grid capacitor C-3 while its other terminal 17 is connected to ground. A conventional grid leak R-3 is connected across capacitor C-3,

or it may be connected between control grid 11 and ground with equal or similar results. An inductance L-2, coupled to inductance L-1 of the tank circuit L-1, C-1, is connected between cathode 10 and ground.

A capacitor C-4 of appropriate value is connected between terminal 16 of the tank circuit and plate 14 of the tube. Suppressor grid 13 is connected to terminal C which is connected to a vibrato oscillator 18 capable of generating a vibrato signal of very low frequency, such as approximately 6 cycles per second.

From the foregoing description, the operation of the master oscillator embodying the invention will be readily understood by those skilled in the art. Referring first to the first triode section of tube V-1 constituted by cathode 10, control grid 11 and screen grid 12, it will be noted that this electrode together with tank circuit L-1, C-1 and the other circuit elements electrically associated therewith form a tuned grid oscillator, feedback between the grid and the plate circuits being provided by the coupling between inductances L-1 and L-2. Electrical oscillations will be produced in this circuit in a manner well understood, the frequency of said oscillations being determined by the value of inductance L-1 and capacitance C-1. As most of the electrons emitted by cathode 10 miss screen grid 12, a substantial portion of such electrons will proceed to plate 14. An oscillatory signal of the produced frequency may be withdrawn at the plate and may be applied to the octavely related cascaded oscillators as this will be set forth more fully in the following.

Screen grid 12, suppressor grid 13 and plate 14 of tube V-1 operate as a second virtual triode, the screen grid functioning as the cathode, the suppressor as the control grid and the plate as the anode. Therefore, the vibrato signal of vibrato oscillator 18 will vary the effective plate resistance of the second triode at the vibrato rate and will act as a conducting path of variable resistance effectively connecting capacitor C-4 to capacitor C-1 of the tank circuit. This will cause frequency modulation and to a minor extent also amplitude modulation of the oscillations withdrawn.

It will be noted that the vibrato system of the invention embodying the frequency modulated master oscillator just described provides various important advantages. The most important of these is that no individual triode or modulator tube is required for each master oscillator since the same pentode tube serves both as the usual electron coupled oscillator and the frequency modulator tube. Another important advantage of the circuit is that the inherent frequency stability of the electron coupled oscillator is retained since changes in both the screen current and anode current are reflected to the oscillatory circuit as a frequency shift so that by proper manipulation of the electrode voltages the shift due to the one may be caused to exactly cancel the shift due to the other. This cancellation, however, does not affect the frequency modulating or vibrato circuit, since there only the plate current is varied. In order to obtain maximum frequency stability, it is necessary, however, that the anode 14 and the screen grid 12 be supplied from the same source, using a voltage divider network as shown in the form of tapped resistance R-2 in Figure 1. It is perfectly satisfactory to connect the screens of all master oscillator tubes together and to supply them from a single voltage

divider network provided that the anodes of all tubes are supplied from the same source. It will further be noted that the suppressor grids of all master oscillator tubes may be tied together and supplied from a single vibrato oscillator 18, generating a vibrato signal having a frequency of approximately 6 cycles per second. In other words, terminals A, B, and C may be common for all master oscillators of the electrical musical instrument.

In a practical electrical musical instrument generally 12 master oscillators are employed, each of which is tuned to a different note of a single octave of the tempered scale, which in most cases is the highest octave of the range of the instrument. The output of each master oscillator is applied to a cascaded group of octavely related slave oscillators from which the oscillations of musical frequency may be selectively withdrawn in accordance with the requirements of a musical composition by means of switches under the control of a manually operable keyboard.

A system of the described character is diagrammatically illustrated in the block diagram of Figure 2, in which reference numerals 21, 22 and 23 designate three of the twelve master oscillators, each of which has the circuit organization shown in Figure 1. Plate and screen voltages are applied to all master oscillators through a common conductor 24 from power supply 25. The suppressor grids of all master oscillators are likewise connected to a common conductor 26, supplied with the vibrato signal from an oscillator 27. Thus, the output frequencies of all master oscillators will be frequency modulated at the same vibrato rate and will be also amplitude modulated to a minor extent.

The output of each of master oscillators 21, 22, 23, etc. is connected to a cascaded group of octavely related slave oscillators 28, 29, 30, etc. respectively. As a result of these slave oscillators being locked together with each other and with their corresponding master oscillator for synchronous operation, the output of the slave oscillators will be likewise frequency modulated at the same vibrato rate while the slight amplitude modulation present in the output of the master oscillator will be removed. A plurality of groups of switching keys diagrammatically indicated by reference numerals 31, 32, 33, etc. is provided to selectively withdraw musical oscillations of the desired frequencies into a common output bus bar 34 from which the signals may be introduced into an amplifier and may be converted into sound by means of a loudspeaker. Of course, in a practical musical instrument various additional refinements may be employed to modify the wave form of the output signal and thereby to obtain various musically desirable tone colors. For full details of such arrangements and also of preferred forms of octavely related cascaded slave oscillators reference may be had to the aforesaid Larsen patent, #2,403,090, also the disclosure in copending application Ser. No. 702,742.

The vibrato oscillator employed in the vibrato system of the invention may be of any suitable type capable of producing oscillations of very low frequency, in the order of 6 cycles per second with a good waveform of generally sinusoidal character. An oscillator of the so-called "phase-shift" type which is particularly advantageous for the purposes of the invention is illustrated in Figure 3 of the drawing. For details of the construction and operation of this oscillator

reference may be had to the textbook "Theory and Applications of Electron Tubes" by H. J. Reich, 2nd edition, page 398.

Referring now more particularly to Figure 3 of the drawing, there is provided a triode V-2, having a cathode 35, a control grid 36 and an anode or plate 37. Plate voltage is supplied to anode 37 through a resistance R-4. A resistance-capacity network comprising capacitors C-5, C-6 and C-7 and resistances R-5, R-6 and R-7 is connected in the anode circuit of the said triode and is calculated to impart a phase shift of 180 degrees to any signal of appropriate frequency impressed upon the anode. As there is in any vacuum tube an inherent phase shift of 180 degrees between the grid and the anode, the signal at the junction of C-5, R-5 will be 360 degrees out-of-phase with respect to the initial signal at the grid. As in any recurrent wave, a phase shift of 360 degrees is the same as zero phase shift, any signal applied to grid 36 of tube V-2 will be returned to said grid after amplification in the tube in such a manner as to cause the production of sustained oscillations. The frequency of said oscillations is determined by the relative values of C-5, C-6, C-7 and R-5, R-6, R-7, since for any particular set of values of the circuit constants there will be only one frequency at which the phase shift will be exactly 180 degrees. In actual practice this circuit will start oscillating due to any slight fluctuation in electrode voltages or tube characteristics and, once the tube started to oscillate, it will continue to produce oscillations of stable frequency in the manner described in the foregoing. Because of the losses in the phase shift network, a certain minimum gain is necessary in the amplifier circuit in order to sustain oscillation. It can be shown that this gain has to be in the order of 29.

For best results C-5 should equal C-6 and C-7 and R-5 should equal R-6 and R-7 in the phase shift network. However, small variations in frequency due to standard tolerances in the components may be compensated for by making corresponding adjustments on any one of the above elements.

In the "phase-shift" oscillator just described, the frequency of the oscillations and their stability will directly depend upon some particular phase shift. Therefore, any loading of the oscillator will tend to change the frequency or to stop oscillation altogether. For this reason, it is necessary to interpose an amplifier between the output of the oscillator circuit and the load circuit. This amplifier may be a triode, such as tube V-3 shown in Figure 3, having a cathode 38, a control grid 39 and a plate 40. Cathode 38 of tube V-3 is directly connected to cathode 35 of tube V-2 and grid 39 of tube V-3 is directly connected to grid 36 of tube V-2. Grid bias is obtained by means of a common cathode resistor R-8 connected between the cathode and ground and having a by-pass capacitor C-8 connected across the same. Plate voltage is applied to anode 40 of tube V-3 through a resistance R-9 and the amplified oscillations of low frequency are applied to the load, that is to the suppressor grids of the master oscillators, through a coupling condenser C-9.

Since the cathode and grid circuits of the oscillator and amplifier tubes V-2 and V-3 may be connected in parallel, the circuit readily lends itself to the use of a high-mu dual triode, such as the tubes type 6SL7 or 6SC7.

The circuit just described has important ad-

vantages over the Van der Pol oscillator and other negative resistance oscillators used for generating very low frequencies. Of greatest importance among these advantages are the excellent waveform and the small physical size of the components necessary to generate oscillations having a frequency of approximately 6 cycles per second as is normally required in a vibrato system for musical instruments. Other advantages are the great stability of oscillation and the fact that the oscillation frequency is in no way a function of the tube characteristics, such as the plate resistance, transconductance, etc.

The electrical values of the elements as numbered and lettered on the drawings and several circuits and networks and preferred types of vacuum tubes employed are, approximately, as follows:

	Condensers	Resistors	Coils	Tubes
20				
1. .035	1. 22K	1. 170 m _k	1. 6SK7	
2. 10 mfd	2. 15K	2. 15 m _k	2. 6SL7	
3. .002	3. 50K		3. 6SL7	
4. .002	4. 50K			
5. .05	5. 250K	K=.77		
6. .05	6. 250K			
7. .05	7. 250K			
8. 25 mfd	8. 3300 Ω			
9. .1	9. 50K			

I have described use of my invention in a system employing 12 master oscillators. Resistance R₂ which is common to all master oscillators has an entire resistance of 15 K, and is tapped at 10 K, as shown at Figure 1.

The coefficient of coupling, coils L₁ and L₂ is approximately .77, being the average position of the iron core.

Although the present invention has been described in connection with a preferred embodiment thereof, variations and modifications may be resorted to by those skilled in the art without departing from the principles of the invention. I consider all of these variations and modifications to be within the true spirit and scope of the present invention, as disclosed in the foregoing description and defined by the appended claims.

What is claimed as my invention is:

1. In an electrical musical instrument, a frequency-modulated generator of audio frequency electrical oscillations which comprises a space-discharge tube having at least a cathode, a plate, a control grid, a screen grid and a suppressor grid; means including an oscillatory circuit electrically associated with said cathode, said control grid and said screen grid to produce electrical oscillations of audio-frequency in said circuit; a high resistive load circuit; connections from said plate and screen grid to spaced points in said high resistive load circuit, and means for impressing a signal having vibrato rate upon said suppressor grid whereby the frequency of the oscillations produced in said oscillatory circuit will be modulated at said vibrato rate.

2. In an electrical musical instrument, a frequency-modulated audio frequency oscillation generator which comprises a space discharge tube having a cathode, a plate, and control, screen and suppressor grids; said cathode, control grid, and screen grid constituting a first triode unit and said screen grid, suppressor grid and plate constituting a second triode unit, the first and second triode units being electron coupled to each other; means including an oscillatory circuit electrically associated with said first triode unit to produce audio-frequency oscillations therein and

to make such oscillations effective in said second triode unit; a high resistance connected between said plate and cathode, a tap on said high resistance connected with said screen grid; and means for varying the effective plate resistance of said second triode unit at a vibrato rate thereby to frequency-modulate at such rate the oscillations generated in said first triode unit.

3. In a frequency-modulated oscillation generator for electrical musical instruments, the combination which comprises a space discharge tube having at least a cathode, a plate and control, screen and suppressor grids; said cathode, control grid and screen grid constituting a first triode unit of which the screen grid is the plate and said screen grid, suppressor grid and plate constituting a second triode unit of which said screen grid is the cathode; said first and second triode units being effectively coupled to each other by the transfer of electrons from one unit into the other; means electrically associated with said first triode unit to cause a flow of electrons varying at a musical frequency rate through both triode units; a high resistance circuit connected between said plate and cathode, a tap in said high resistance circuit leading to said screen grid means including a vibrato oscillator for varying the effective plate resistance of and the flow of electrons through said second triode unit at vibrato rate thereby to frequency-modulate said electron flow at such rate; and coupling means for withdrawing frequency-modulated oscillations of musical frequency from at least one of said triode units.

4. In an electrical musical instrument, the combination with a plurality of frequency-modulated generators; each of said generators comprising a pentode tube, having a cathode, control grid, screen grid, suppressor grid and a plate and in which the cathode, control grid and screen grid constitutes a first triode unit and the screen grid, suppressor grid and plate constitutes a second triode unit electron coupled to the first unit; connections supplying plate and screen voltages to all of said pentode tubes from a common source of current; a set of reactive circuit elements for the first triode unit of each pentode thereby to produce oscillations of musical frequency therein; a vibrato oscillator having its output directly connected to the suppressor grid of each pentode to simultaneously apply oscillations of vibrato frequency to the second triode unit of each pentode thereby to frequency modu-

late said oscillations of musical frequency at a common vibrato rate; a high resistance circuit connected between said plate and cathode, a tap in said high resistance circuit leading to said screen grid and coupling elements individual to said pentodes to withdraw frequency-modulated oscillations therefrom, the frequency of said oscillations and the rate of their modulation being substantially independent from variations in the voltage of said common source of current.

5. In an electrical musical instrument, the combination which comprises a group of twelve electron-coupled master oscillators, each including a pentode tube including a cathode, control grid, screen grid, suppressor grid and a plate, a tank circuit electrically associated with the cathode and control grid and tuned to a musical frequency corresponding to a different note of a single octave of the tempered scale, a common source of plate and screen voltages for said tubes to cause the generation of oscillations of described frequencies by said master oscillators and to render such oscillations effective in the respective plate circuits of said tubes, a high resistance circuit connected between said plate and cathode, a tap in said high resistance circuit leading to said screen grid, a common vibrato frequency oscillator having its output directly connected to the suppressor grids of all of said tubes thereby to frequency modulate said musical oscillations at vibrato rate, a cascaded set of octavely related slave oscillators for each of the said master oscillators locked in with but effectively isolated therefrom, and key-controlled switching means to selectively withdraw oscillations from said slave oscillators, each of said withdrawn oscillations being octavely related to one of the master oscillators and all of the withdrawn oscillations being frequency modulated at the same vibrato rate.
